UNITED STATES PATENT OFFICE.

WALTER I. WEBBER, OF LOS ANGELES, CALIFORNIA.

COMPUTING DEVICE.

1,138,817.

Specification of Letters, Patent.

Patented May 11, 1915.

Application filed January 27, 1914. Serial No. 814,850.

To all whom it may concern:

Be it known that I, WALTER I. WEBBER, a citizen of the United States, residing at Los Angeles, in the county of Los Angeles and State of California, have invented a new and useful Computing Device, of which the following is a specification:

This invention relates to a computing device for calculating the probabilities or relations of associated classes of data, for example, exchangeable lists, scales, charts or tables, or portions or combinations thereof, such as those giving multiples or fractions of base rates of wages, interest, rents, valuations, incomes, taxes or insurance; or those presenting computations, reports or statistics of production, consumption, costs, depreciation, values, prices, discounts, profits, losses, sales, purchases, weights, contents, distances, speed, fuel consumption, time, stock fluctuations, imports or exports; or schedules of passenger fares, freight charges, express tariffs or postage rates.

The invention is herein illustrated as applied to the computation of handicaps for race horses. It will be understood that by suitable modifications in the data-figures on the several elements of the device, it may be adapted to other computations.

The main object of the invention is to supply means whereby such computations may be made quickly by a process of mechanical operation and inspection, as distinct from mental calculations.

A further object of the invention is to provide means whereby a large number of computations of intricate character may be made quickly and easily.

Other objects of the invention will appear hereinafter.

The accompanying drawings illustrate an embodiment of my invention, and referring thereto: Figure 1 is a front elevation of the device, the inclosing case being shown open to expose the computation means. Fig. 2 is an end elevation of the inclosing case in closed position. Fig. 3 is a vertical section of the device. Fig. 4 is an end elevation of the data drum.

The device is mounted in a suitable case 1, provided with an opening 2, and having a cover 3, hinged to the case at 4, and adapted to close said opening. Within the case 1, is mounted a drum 5, carried by a shaft 6, mounted to turn in bearings at the ends of the casing 1, and provided with operating

handles or knurled wheels 7, outside of the case. On said drum or on a sheet, or cylinder extending around said drum, are provided marks, 8 and 9, representing data which enter into the computations to be made, these marks being exposed through a slot 10, in a plate 11, which extends over the opening 2, in the case 1. Marks 8, are arranged in an annular series around the drum, and correspond, in the assumed case of race handicap computations, to the length of the various courses to be run. A row of marks 9, extends longitudinally of the drum in line with each of the marks 8, said marks 9 representing the times in which the courses may be traversed, in minutes, seconds, and fifth-seconds. Below said slot 10, is a strip 12, carrying a series of numbers or marks 13, corresponding to other data entering into the computations, or in the particular case here shown, corresponding to handicap "points." Below this strip 12, is mounted a sliding correction scale 14, slidable longitudinally in guideway 15, so as to bring a pointer or index 15', on said slide, opposite any one of the point marks 13, on the strip 12. Said slide is, in the present case, provided with an upper row of numbers indicated at 19, their intervals corresponding to those of the arbitrary points on the fixed scale, and representing horse lengths or one-fifth seconds; and the lower numbers indicated at 20 corresponding to excess or deficiency of pounds carried by the horse. Said slide 14, is provided at one or both ends with up-turned lugs at 23, to facilitate manipulation of the slide. These marks 20, corresponding to weight, may be spaced uniformly as shown at the left of the index 15, or they may be spaced at progressively increasing intervals, as shown at the right of said index, so as to provide for an increased proportionate allowance for large excess of weight.

In using this computing device for predicting the position of a horse at the finish of a coming race, suitable scales, tables, or charts (form sheets) are used in connection with the device. These published records or form sheets give the distance traversed, the names of the contending horses, the weights carried by each, their order at the finish, the distance in lengths which each beat the next behind him, and the time in minutes, seconds, and fifths of a second in which the race was beaten. In predicting

the future ability of a horse from his previous performance, the drum 5 is turned by one of its handles 7, so as to bring into view, through the slot 10, the mark in the annular series 8 which represents the length of the course or distance traversed in the said previous race. This also exposes one of the rows of marks 9, corresponding to the time in which races of that distance may have been beaten. The sliding scale 14 is then moved so as to bring the index thereon directly below the mark or figures corresponding to the time in which the said former race was in reality beaten. If a three furlong race, in which the horse being handicapped contended, was beaten by another horse in thirty-five and three fifths seconds, the index is moved to bring it beneath the mark in the row 9 corresponding to that time, as shown in Fig. 1. It will then be beneath the eighty-eight point mark of the fixed scale 13. By means of the sliding scale 14, a correction is then made for the performance of the horse being handicapped, as compared with the above named winning horse. Suppose for example the horse to be rated was beaten by the winner seven lengths, the position of the figure 7 in the row of marks 19 at the right of the indicating arrow of the sliding scale 14 is observed with reference to the figure above it on the fixed scale 13, and the sliding scale 14 is then moved to bring its index below the new number 81 thus indicated. This figure 81 now represents the standing of the horse as corrected by his finishing position in his former race. A correction is now made for the difference in weight to be carried by the horse in his coming race, as compared with the weight carried by him in his former race. If he is to carry five pounds more in his coming race than in his former one, then his rating will be shown by a lower figure of the fixed scale 13. The sliding scale 14 having been moved until its index points to the figure 81 of the fixed scale 13, the 5 in the progressive pound scale 20, at the right on the index, will then be beneath the 78 of the fixed scale 13, which figure 78 will be the horses prospect-figure for his coming race. Prospect-figures having been similarly obtained for all other horses entered for the future event, their relative powers will thus be indicated. If the said horse be assigned fewer instead of more pounds in the coming race, his chance of winning will

be better instead of poorer, and will be represented by a higher figure of the fixed scale 13. The index of the sliding scale 14 having been moved to point to the figure 81 of the fixed scale 13, the 5 of the pound scale 20 at the left of the index will come beneath the figure 84 of the fixed scale 13, which figure 84 will then represent his prospect for the coming race. 65

The device is capable of being used for various other purposes by proper modification of the several series of data marks carried by the different members thereof. 70

What I claim is:

1. In a computing device an element carrying data, a fixed scale, and a slidable scale carrying two sets of graduations, the first set of graduations being read in conjunction with the data and the fixed scale, and the second set of graduations being readable in conjunction with the fixed scale. 75

2. In a computing device a rotatable element carrying data, a fixed scale to be read in conjunction with said data, and a slidable scale having two series of graduations, the first series of graduations being read in conjunction with said fixed scale and data, the second series of graduations being arranged progressively and readable in conjunction 85 with the fixed scale.

3. A computing device comprising a rotatable cylinder bearing a plurality of longitudinal rows of data marks arranged in different positions along a cylinder and bearing also an annular series of data marks extending around the cylinder, the respective data marks of the last named series registering with the respective rows of the first named data marks, a fixed scale extending 95 longitudinally of the cylinder and adjacent thereto, and a slidable scale movable longitudinally adjacent to said fixed scale and provided with two longitudinal series of graduations, the graduations of one series 100 being progressive and being read in conjunction with the fixed scale and the other series of graduations on the slidable scale being read in conjunctions with the data of the cylinder and also the fixed scale. 105

In testimony whereof, I have hereunto set my hand at Los Angeles, California, this 20th day of January, 1914.

WALTER I. WEBBER.
